CLAIM

The ornamental design for a brush with removable bristle elements, as shown and described.

DESCRIPTION

FIG. 1 is a perspective view of a brush with removable bristle elements of my new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a rear elevational view thereof;

FIG. 7 is a front elevational view thereof; and,

FIG. 8 is an exploded, perspective view with only two bristle elements shown, the remaining bristle elements shown removed to show aspects of the design not clearly visible when combined.

1 Claim, 5 Drawing Sheets
